Primary Examiner — Karen S Acker*(74) Attorney, Agent, or Firm* — George H. Leal**CLAIM**

The ornamental design for an absorbent pad with pattern, as shown and described.

DESCRIPTION

FIG. 1 is a perspective view of an absorbent pad with pattern shown in a curved position;

FIG. 2 is a top view of the absorbent pad with pattern in a flat position;

FIG. 3 is a bottom view thereof;

FIG. 4 is a left side view thereof;

FIG. 5 is right side view thereof;

FIG. 6 is a front side view thereof; and,

FIG. 7 is a back side view thereof.

All broken lines in the drawing depict environmental subject matter that forms no part of the claimed design. The innermost broken line on the top view also forms a boundary to the claim.
